United States Patent Office

Des. 222,695
Patented Dec. 7, 1971

222,695

FIRE HYDRANT

John J. Smith, Decatur, Ill., assignor to
Mueller Co., Decatur, Ill.

Filed May 11, 1970, Ser. No. 22,904

Term of patent 14 years

The portion of the term of the patent subsequent to
Aug. 18, 1984, has been disclaimed

Int. Cl. D23—01
U.S. Cl. D23—12

Fig. 1.

Fig. 2.

FIG. 1 is a top plan view of a fire hydrant embodying my new design;

FIG. 2 is a perspective view taken from the top and front thereof;

FIG. 3 is a perspective view taken from the top and one side thereof, the opposite side being a mirror image of the side shown; and

FIG. 4 is a perspective view taken from the top and rear thereof.

I claim:

The ornamental design for a fire hydrant, as shown and described.
